UNITED STATES PATENT OFFICE

CLAUDE L. POST, OF CHICAGO, ILLINOIS

PRINTING MECHANISM

Application filed October 3, 1924. Serial No. 741,428.

My invention belongs to that general class of devices known as printing and feeding mechanisms, and relates more particularly to a high speed printing press adapted to be employed for printing envelopes, cards, sheets, etc., and adapted for use with plates or linotype slugs or the like. The invention has among its objects the production of a machine of the kind described that is simple, reliable, compact, efficient, satisfactory for use wherever found applicable, and capable of operation at high speed. The invention has more particularly among its objects the production of a machine provided with an improved inking mechanism, a machine which is more accessible, which may be easily adjusted in changing from plates to linotype slugs, which feeds more accurately, and which will operate at high speed without slurring or blurring in the printing. Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a plan view of a portion of my improved machine;

Fig. 2 is a side elevation of the same;

Fig. 3 is a side elevation of the opposite side, a portion of the parts being omitted;

Fig. 4 is a sectional view taken substantially on line 4—4 of Fig. 1;

Fig. 5 is a view in elevation of the mechanism shown in Fig. 2, looking substantially along line 5—5 of Fig. 2;

Fig. 6 is a sectional view taken substantially on line 6—6 of Fig. 5;

Fig. 7 is a sectional view taken substantially on line 7—7 of Fig. 1;

Fig. 8 is a sectional view taken substantially on line 8—8 of Fig. 1;

Fig. 9 is a face view of a portion of the printing roll;

Fig. 10 is a section taken substantially on line 10—10 of Fig. 9;

Fig. 11 is a section taken substantially on line 11—11 of Fig. 13;

Fig. 12 is a section taken substantially on line 12—12 of Fig. 2; and

Fig. 13 is a section taken substantially on line 13—13 of Fig. 2.

Referring to the drawings, in which the preferred embodiment of my invention is shown, it may be mentioned that I have not shown details of all of the various parts or operating mechanisms, as these are shown in my preceding applications in detail and may be varied as found desirable. The following applications and patents may be mentioned: application Serial Number 627,455 filed March 24, 1923; U. S. Letters Patent 1,531,812 dated March 31, 1925; U. S. Letters Patent 1,513,858 dated November 4, 1924 and U. S. Letters Patent 1,481,557 dated January 22, 1924. The particular machine shown consists of the main frame portion 1 of suitable size, shape and material, upon which is rotatably mounted the printing roll 2 and impression roll 3, the parts being driven from a drive shaft 4. In the machine illustrated, shaft 4 is driven by means of a disk 5 mounted thereon and cooperating with a friction wheel 6 adjustably mounted on shaft 7 and driven by an electric motor 8 or other source of power. The envelopes or other devices to be printed upon are placed in the magazine or hopper on table 9, are fed through the machine and discharged at the opposite side.

In view of the fact that I have illustrated a machine particularly adapted for the printing of envelopes, I have shown a flap-turning mechanism in connection with the magazine of the machine, it being understood, however, that the details of construction of this particular mechanism forms no part of the invention herein claimed, the same being described more in detail in the aforementioned pending cases and patents. The construction of the machine is such that the articles to be printed upon, regardless of what they are, are fed through the machine and printed upon at high speed and the mechanisms are therefore designed for high speed work. The machine

is so constructed that if there are no sheets fed through, the machine will automatically stop, and likewise the printing roll and impression roll will be separated. This need not be described in detail herein.

I have illustrated in Figs. 9 and 10 my improved type of printing roll 2, the same being adapted for printing by means of plates or to use linotype slugs or the like. Referring particularly to these figures, roll 2 is provided with a longitudinal groove 12, in which may be placed the slugs 13 separated by the spacers 14, the face 15 of the slugs projecting above the roll. The slugs are maintained in place by rings 16 having turned over portions 17 adapted to engage in the slots 18. Any equivalent securing means may be employed, but this is simple and particularly efficient. The slugs are engaged at their edges below the face 15 thereof. The spring segments 16 may be slipped on or off over the ends of the slugs, holding the slugs and spacers in place when they are in operative position. The roll may be provided with one or more slots 19 for the securing of plates to the roll in a similar manner, or in any equivalent manner.

I have also illustrated in Figs. 9 and 10 the ring members or semi-ring members 20 which extend over the roll and may be moved into adjusted positions thereon. These ring members are formed to substantially fit the roll and are secured in place by constructing one end as indicated at 21 and the other end lying flat on the roll, the length of the same and spring tension holding the same in place. These are employed both with plates and slugs. In the operation of the machine, these rings, particularly in the case of cards and envelopes, tend to steady the object to be printed upon and prevent movement of the same or slurring, as it may be termed, whereby the print is not sharp and exact.

The type or printing plate on the printing roll 2 is inked through suitable ink-carrying rolls arranged between the ink reservoir 24. As shown, the preferred embodiment consists of rolls 25, 26, 27, 28, 29, 30 and 31, roll 26 being adapted to periodically transfer ink from the roll 25 to the roll 27, from which it is carried in regular order on to the printing roll 2. The rolls 27 to 31 may be rotated in any suitable manner, roll 29 being usually positively driven and the others driven by a contact therewith or with each other. The roll 25 is rotatably mounted in the frame brackets 32, and is arranged to cooperate with the reservoir wall 33 which is shown substantially yieldable and controlled by means of the desired number of thumb screws 34 arranged across the reservoir (see Fig. 1). Roll 25 is mounted on a suitable shaft carried by the frame 32 and provided with the ratchet wheel 35 at one end. Pivots mounted on the shaft is an arm 36, the

same being pivotally secured to the shaft by means of a screw 37 or equivalent means for the purpose. At the opposite end 38 of arm 36 is arranged a pawl 39, this being pivotally secured to the arm by a pin 40. The function of the pawl is to rotate the ratchet 35 in a step-by-step movement when the arm 36 is actuated. Arm 36 is controlled by a pin 41 or the equivalent carried by a shaft 44.

As most clearly shown in Figs. 5 and 12, the pin is arranged in the hub 45 of a ratchet wheel 47, the hub 45 and a collar 46 maintaining the shaft in proper relation in the bearing formed on the frame 32. Pivotally carried by shaft 44 is an arm 48, same being secured to the shaft by a pivot pin 49 or equivalent means. Secured to the arm 48 by a pin 51 or the equivalent is a pawl 50 for actuating the ratchet 47. Arm 48 is connected with the link 54 pivotally secured to the arm 85 by a pin 55 at one end and at its opposite end to collar 57 by a pin 55^a or the equivalent, the collar 57 being secured on the shaft 58, forming a part of the printing roll.

I generally prefer to provide a plurality of holes 56 so that the position of the pin 55 may be varied so as to vary the movement of the parts. Obviously, as the shaft end 58 is rotated, pin 56^a being eccentric to the center of the shaft, causes arm 48 to be rocked back and forth on the pin 49, and this movement through the pawl 50 actuates the ratchet wheel 47, rotating shaft 44. At each complete rotation of the shaft, pin 41 rocks the arm 36 and this through the pawl 39 moves the ratchet wheel 35 in a step-by-step movement, thereby similarly moving the roll 25.

The roll 26 is rotatably carried on a swinging frame 60 pivotally supported from the part or brackets 32 at 61. A spring 62 or equivalent means tends to normally pull the roll 26 into contact with the roll 25, as indicated in the full lines in Fig. 4. Arranged on shaft 44 is a cam 65 arranged to cooperate with the roll or suitable part 66. As the cam 65 rotates with the shaft 44, it rocks the frame 60 toward the printing roll, thereby bringing roll 26 into contact with roll 27, and as the shaft further rotates the spring draws it back into contact with roll 25. It will thus be seen that the ink from roll 25 is carried periodically to roll 27 by means of the roll 26.

In a machine of this type where the area printed is comparatively small, it will be obvious that not as much ink is required as in the case of a machine required to ink a large type surface, and the arrangement shown provides ample ink for the printing roll and yet avoids a surplus of ink. Obviously, by providing the intermittent drive of the roll 25 and the intermittent transfer of ink from that roll to roll 27, a very nice balance between the ink actually fed and the ink actually required may be maintained at all times.

Arranged between the magazine and the printing roll is suitable carrying mechanism which carries the sheets, cards, envelopes or the like from the magazine to the roll. The carrying mechanism shown comprises a frame 5 69—70, suitably carried from the main frame 1, upon which frame is mounted carrying mechanism. This frame is preferably removably mounted on frame 1, the carrying mechanism being substantially a separate unit 10 carried thereby which may be set or adjusted so as to adjust the feed in a predetermined manner for different jobs; and also to permit quick changes from linotype slugs to plates 15 on the type or printing roll. As shown, the frame is provided with recesses 72 and the carrier frame with lugs 71 arranged to seat therein. The opposite end of the frame carries a shaft 73 which seats in open bearings 20 in the main frame 1 and is driven in the manner hereinafter described. Shaft 73 carries sprockets 75, over which are arranged chains 76. These chains run over sprockets 77 arranged on the rear shaft 73' (see Fig. 7). The chains are provided with work-engaging 25 members 78, which engage the edge of the sheet fed on to the chain and carry it along to the printing roll.

As most clearly shown in Fig. 3, the shaft 30 73 is provided with a pinion 79 meshing with the pinion 80, and this through pinion 81 and intermediate gearing or the equivalent is driven from the main drive shaft 4. Obviously, by lifting the forward end of the 35 frame 69—70, pinion 79 may be turned by hand so as to vary the adjustment of the chains relative the printing roll, after which the frame may be dropped into engagement with the main frame, bringing pinions 79 and 80 into driving engagement again. Likewise, 40 if desired, the entire carrier frame may be removed for any purpose found necessary. For example, it is generally more convenient to work on the printing or impression roll 45 with the conveying mechanism removed, and with this construction it is a simple matter to remove it.

As most clearly shown in Figs. 1 and 7, the frame 69—70 is provided with a chain support 82 and carries the guides 85—86, between which the envelope, card or sheet is fed from the magazine. I have shown feeding 50 wheels 87 arranged on the shaft 73'. It will be noted that the guides 85 and 86 are so arranged at the free end as to receive the paper or the like without danger of its being crumpled up. I have shown a roll 88 provided 55 with a bearing shaft 89 mounted in the brackets 90. This feeding means receives the envelope or the like from the magazine discharging mechanism and conveys it to a point on the guides 85 and 86, where it may be picked up by the engaging members 78. The 60 weight of the material itself merely resting 65 on the feeding wheels 87, ordinarily would

not be sufficient to cause the material to be fed, but by employing the roll 88, this maintains the material in feeding engagement with the wheels 87. Resting upon the sheet or the like passing through the machine it. 70 to some extent, also retards the momentum of the same until the sheet or card reaches the point where it is picked up by the engaging members 78. Ordinarily, its weight is sufficient 75 to cause it to function perfectly without additional mechanism.

Referring particularly to Fig. 4, 93 is an arm mounted on a shaft 94, the function of this arm being to turn down the flap of the envelope when envelopes are being passed through the machine. This arm swings about shaft 94 as a center substantially as shown in Fig. 4 in the full lines, in which it is in its raised position. Shaft 94 is provided with an arm 95 arranged at the outside of the frame 1. On the end 96 of the impression roll is arranged a cam 97 arranged to cooperate with the lever 98 pivotally secured at 99 to the frame of the machine, the opposite end 100 being adapted to cooperate with the arm 95. 101 represents a stop arranged on the frame, and 102 represents a spring (see Fig. 13) which tends to maintain the shaft so that the arm 93 is as shown in Fig. 4. As the shaft 96 rotates, turning the cam 97, this 93 actuates lever 98, the end (100) of which bears on the arm 95, depressing the same so as to move the shaft 94 in a direction to lower the arm 93. As the cam rotates and releases lever 98, spring 102 brings the parts 100 back substantially as shown in Fig. 4.

As before mentioned, the device herein shown is particularly adapted for high speed work, and it is therefore especially satisfactory for use in printing envelopes, cards and the like. The same is suitable for printing by means of type or printing plates, and is so constructed that it is not only easily accessible but changes and adjustments may be made in a minimum of time. This is particularly desirable in work of the nature set forth as owing to the high speed of operation, the same may be easily changed for different set-ups and sizes and the time saved in high speed operation is not lost in adjustment 115 work. It is a simple matter to change from plates to slugs or vice versa.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a printing machine of the kind described and in combination, a printing roll, printing means and means for securing said

- printing means on the roll, and work-engaging means adjustably mounted on the printing roll consisting of resilient metallic ring segments constructed to operatively engage with the roll, said segments arranged to contract upon the impression roll and prevent slurring of the printed sheet passing between the rolls.
2. In a printing machine of the kind described and in combination, a grooved printing roll, printing means and means for securing said printing means on the roll, and work-engaging means adjustably mounted on the printing roll consisting of ring segments constructed to conform to and overlie a portion of the roll, one end constructed to operatively engage with the roll groove with the other end formed to embrace the roll and be maintained thereon by engagement with the roll at the surface, said segments arranged to cooperate with the impression roll during a printing operation and prevent displacement of the printed sheet passing between the rolls.
3. In an envelope printing device of the kind described and in combination, a main frame, printing mechanism, and means for folding the envelope flap after the same has passed through the printing mechanism, consisting of a folder arm, a rock shaft carrying said arm projecting to the exterior of the frame of the machine, resilient means for normally maintaining said folder arm in operative engaging position, and means on said shaft at the exterior of the main frame for actuating said shaft.
4. In an envelope printing device of the kind described and in combination, a main frame, printing mechanism, and means for folding the envelope flap after the same has passed through the printing mechanism, consisting of a folder arm, a rock shaft carrying said arm projecting to the exterior of the frame of the machine, resilient means for normally maintaining said folder arm in operative engaging position, and means at the exterior of the main frame for actuating said shaft, including a cam carried by the printing mechanism, a cooperating lever pivotally secured to the frame at the exterior thereof, and an arm secured on said folder arm shaft and arranged to cooperate with said lever during its actuation by said cam.
5. In a machine of the kind described and in combination, a frame, printing mechanism carried thereby, driving means for said printing mechanism, a material magazine, conveying means for conveying material from said magazine to said printing mechanism, said conveying means removable as an entirety from the machine and consisting of a frame, a conveyor carried thereby, driving means for the conveyor, arranged to operatively engage with the printing driving means when the frame is seated and to disengage therewith

when the frame is lifted, whereby the conveying means may be disengaged and adjusted independently of the printing driving means and printing mechanism.

6. In a machine of the kind described and in combination, a main frame, printing mechanism carried thereby, inking means, driving means for said printing mechanism and inking means, a material magazine, conveying means between said magazine and said printing mechanism, said conveying means removable as an entirety from the machine consisting of a frame, a conveyor and feeding means therefor carried thereby, driving means for the conveyor and feeding means, said driving means arranged to operatively engage the printing driving means when the frame is seated and to disengage therewith when the frame is lifted, whereby either the conveying means or the printing mechanism may be adjusted independently of the other by lifting the conveying means frame from the main frame.

7. In a machine of the kind described and in combination, a main frame, driving mechanism on said main frame, printing mechanism carried by said main frame, and means for conveying material to be printed to said printing mechanism, said conveying means comprising a frame movably mounted on the main frame, conveying means carried by said movable frame, means on said movable frame for driving the conveying means carried thereby, said driving means on said movable frame being operatively engageable with said driving mechanism on the main frame when the movable frame is in its operative position, and said driving means on said movable frame being readily adjustable with respect to the driving mechanism on the main frame when the movable frame is in an inoperative position.

8. In a machine of the kind described and in combination, a main frame, driving mechanism on said main frame, printing mechanism carried by said main frame, and means for conveying material to be printed to said printing mechanism, said conveying means comprising a frame movably mounted on the main frame, conveying means carried by the movable frame, means carried by the movable frame for driving the conveying means carried thereby, said driving means on said movable frame being adapted to operatively engage said driving mechanism on said main frame when said movable frame is moved into its operative position with respect to the main frame, and said conveying means carried by said movable frame being readily adjustable when said driving means carried by said movable frame is not in operative engagement with said driving mechanism carried by said main frame.

9. In a machine of the kind described and in combination, a main frame, driving mech-

anism on said main frame, printing mechanism carried by said main frame, a magazine, mechanism for conveying material from said magazine to said printing mechanism, said 5 conveying mechanism being movable as a unit into an inoperative position with respect to the main frame, and being adjustable with respect to the timing of said driving mechanism on said main frame when it is in 10 the inoperative position.

10. In an envelope printing device of the kind described and in combination, printing mechanism, and means for folding the envelope flap after the same has passed through 15 the printing mechanism, said folding means comprising a folder arm, a rock shaft carrying said arm, resilient means for normally maintaining said folder arm in a predetermined position, and means including means 20 mounted on said shaft for rocking said shaft.

11. In an envelope printing device of the kind described and in combination, printing mechanism, and means for folding the envelope flap after the same has passed through 25 the printing mechanism, said folding means comprising a folder arm, a rock shaft carrying said arm, resilient means for normally maintaining said folder arm in operative engaging position, and means for oscillating 30 said shaft including a cam carried by the printing mechanism, a pivoted lever engaging said cam, and an arm secured on said shaft and engageable with said lever.

12. In a device of the class described and 35 in combination with a main supporting frame, an auxiliary frame removably mounted on said main frame, said auxiliary frame carrying a conveying device and means for guiding the work to be conveyed, cooperating 40 means on said frames for retaining them in fixed position relative to each other and co-operating means carried by said main and auxiliary frames for driving the conveying device and said driving means of said auxiliary 45 frame being separable from the driving means of the main frame.

13. In a device of the class described and in combination with a main supporting frame, an auxiliary frame removably mounted 50 on said main frame, said auxiliary frame carrying an endless conveyor and means for guiding the work to be conveyed, said endless conveyor having a work-engaging member thereon for advancing the work, co-operating 55 means on said frames for retaining them in fixed position relative to each other, driving means on said main frame, and means on said auxiliary frame detachably connected to said driving means for transmitting motion 60 to said conveyor.

14. In a device of the class described and in combination with a main supporting frame having recesses therein, an auxiliary frame 65 removably mounted on said main frame and having means secured in the recesses thereof,

said auxiliary frame carrying a conveying device and means for driving the conveyor, said means including cooperating elements respectively provided upon the main and auxiliary frames, said element of the auxiliary frame being adapted to be separably connected with said element of the main frame. 70

15. In a device of the class described and in combination with a main supporting frame having recesses therein, an auxiliary frame 75 removably mounted on said main frame and having means secured in the recesses thereof, said auxiliary frame carrying an endless conveyor and means for guiding the work to be conveyed, said endless conveyor having a work engaging member thereon for advancing the work, and driving means on said main frame and means on said auxiliary frame detachably connected to said driving means for transmitting motion to said conveyor. 80

16. In a device of the class described, the combination of a main supporting frame, an auxiliary frame mounted upon said main frame, said auxiliary frame carrying an endless conveyor, a work engaging member provided upon the conveyor, cooperating means on said frames for retaining them in fixed position relatively to each other, driving means on said frames, an element of said driving means of said auxiliary frame providing means for supporting said auxiliary frame. 90

In testimony whereof, I have hereunto signed my name. 100
